UNITED STATES PATENT OFFICE.

BARNA T. STOWELL, OF PERRYSBURG, OHIO.

CORN-PLANTER.

SPECIFICATION forming part of Letters Patent No. 225,660, dated March 16, 1880.

Application filed November 24, 1879.

To all whom it may concern:

Be it known that I, BARNA T. STOWELL, of Perrysburg, county of Wood, and State of Ohio, have invented an Improvement in Corn-
5 Planters, of which the following is a specification.

The following description, taken in connection with the accompanying plate of drawings, hereinafter referred to, forms a full and
10 exact specification, wherein are set forth the nature and principles of the invention, by which the same may be distinguished from others of a similar class, together with such parts thereof as are claimed as new and are
15 desired to be secured by Letters Patent of the United States.

This invention relates to that class of seed-
ing-machines whereby the dropping or planting
20 of the seed is performed by the revolution
of the wheels that carry the machine; and it
25 consists in the construction and novel
arrangement of the various parts thereof, more
fully hereinafter described, and pointed out
in the claim.

25 In the annexed drawings, Figure 1 is a cross-section of my improved machine. Fig. 2 is a front view. Fig. 3 is a detail view of hopper with part of casing removed. Fig. 4 is a plan view of one of the hoppers.

30 A A' denote the wheels of the machine, of ordinary construction, attached to an axle, B, upon which is mounted the body or frame-work of the machine, having in its construction two uprights or vertical standards, C C', and cross-bar c, which support the top piece or platform D, to which the shafts E E' are secured. Forming a part of this frame-work, also, are two hoppers, F F', circular in form, or nearly so, provided with rectangular open-
35 ings f f' for the admission of the grain. On the outer sides and bottoms of these hoppers, or rather the hubs of the wheels A A', are made four slots, g g' g g', two of which form open-
40 ings or recesses into the hoppers F F', and two into the tubes H H', secured to the wheels A A' above mentioned. These hubs are also provided with spring valves or cups g* g*, the object of which is to receive the grain at regular intervals from the hoppers, said valves or
45 50 cups being operated through the medium of

cams on the inside of the hoppers, during which operation the cups are made to deposit, when full of grain, the same down through the tubes H and H' into the chutes or passageways I I, where it falls into the furrow and is planted, said valves being thrown out and operated by cams on the inside of hoppers.

Also secured to the foregoing-described wheels A A', and directly under and in line of the tubes H H', are two chutes or passageways, I I, to the upper parts of which are pivoted valves J J, the longest portions or arms of said valves having their ends bent at right angles to each other, for the purpose of engaging with T-shaped cams fixed in the stand-
ards C C'.

Operation: It will be observed that when the machine is drawn forward and put in motion by the revolution of the wheels the tubes thereon will come directly under and in line of the openings in the hoppers or hubs of said wheels at each revolution thereof, and at the same time the spring valves or cups are thrown outward from the hoppers and open over the tubes through the medium of cams on the inside of the hoppers and the grain is discharged down through the tubes, and the discharge regulated down the chute into the furrows by means of the valves pivoted to said chutes engaging with the T-shaped cams fixed to the standards or frame-work of the machine, the valves being opened when they come in contact with the cams and closed after they have passed the cams, thus effectually accomplishing the planting of the seed.

Having thus described my invention, what I claim as new, and desire to secure by Letters Patent, is—

The combination of the hoppers F F', wheels A A', tubes H H', spring-valves g* g*, open-
90 ings g g', chutes I I, valves J J, and T-shaped cams, all constructed and operating substantially as herein described.

In testimony that I claim the foregoing I have hereunto set my hand this 29th day of September, 1879.

B. T. STOWELL.
